AUTOMATIC RELEASE VALVE

Application filed June 21, 1929. Serial No. 372,595.

This invention relates to the automatic bleeding of the auxiliary reservoirs of automatic air brake systems. As is well known in the art, the automatic system is distinguished from the straight air brake system in that the brakes of the former are applied by a reduction in the pressure in the brake-pipe, also known as the train line, and are released by an increase in the brake-pipe pressure, a valve, termed the triple valve, functioning under the increase in brake-pipe pressure to charge a container, technically known as the auxiliary reservoir, until the pressure of the latter is equal to that of the brake-pipe. When the brake-pipe pressure is reduced, the triple valve operates automatically to permit air to flow from the auxiliary reservoir to the brake cylinder until the pressure in the auxiliary reservoir equals that of the brake-pipe. When the brake-pipe pressure is increased, the triple valve operates automatically to permit the brake cylinder to exhaust to the atmosphere. Manifestly, an accidental break in the brake-pipe, or an intentional disconnection, will cause the brakes to be applied automatically, hence the designation of the system as the automatic air brake system. However, when the braking apparatus of a car is found to be defective and must be disconnected from the brake-pipe, or when certain cars are cut off from the locomotive, as becomes necessary during switching, or when the locomotive is detached from the entire train of cars, the automatic setting of the brakes of the detached cars would make it impossible to move them while they are detached. To obviate this difficulty, the auxiliary reservoirs, prior to the present invention, were provided with manually operated release valves, which were opened to exhaust the auxiliary reservoir, and thereby the brake cylinder, to the atmosphere. It requires about two minutes to exhaust the auxiliary reservoir, and the brakeman or switchman must be at hand to hold the valve open against the urge of the closing spring until the exhaust is completed. The two minutes wait at each car impedes the progress of switching or disconnecting a train, especially where the train is of great length.

Accordingly, an object of the invention is the provision of a release valve for the auxiliary reservoir which may be opened by hand, but will be closed automatically when the brake-pipe is recharged, thereby eliminating the two-minute wait. 55

Another object of the invention is the provision of means whereby the engineer may, if he desires, open the release valves of all the cars of a train automatically when detaching his locomotive, thereby making it unnecessary to open each valve individually. 60

Other objects, advantages, and desirable features of the invention will appear in the course of the following description of an illustrative embodiment of the spirit of the invention. 65

In the accompanying drawing forming part of this specification, in which like numbers of reference denote like parts wherever they occur, 70

Figure 1 is a schematic diagram of the invention; and

Figure 2 is a sectional view of the release valve and adjacent parts, taken on the line 2—2 in Figure 1. 75

Briefly described, the illustrative embodiment of the invention comprises a release valve for the auxiliary reservoir, an air driven motor means for operating the release valve, a connection from the train line or brake-pipe to the motor means for operating the latter to close the release valve, means for entrapping and storing air from the brake-pipe when the pressure in the latter exceeds the normal service pressure, and means for automatically releasing the stored air and conveying it to the motor means for operating the latter to open the release valve when the brake-pipe is discharged. 80 85

The motor means preferably comprises a motor for closing the release valve, and another motor for opening it. The valve closing motor comprises a cylinder 1, having a piston 2 at one end, and the valve opening motor comprises a cylinder 3 having a piston 4, the pistons 2 and 4 being rigidly secured to a common piston rod 5. Preferably, but not necessarily, the release valve is located in one of the cylinders, and preferably in the 90 95 100

cylinder 1, for reasons which will hereinafter appear. To this end, the internal diameter of the intermediate portion 6 of the cylinder 1 is less than the internal diameters of the 5 end portions 7 and 8, and a channel 9 having a flat bottom 10 is formed in the lower internal side of the thicker intermediate wall 6. The flat bottom 10 forms a seat for the release valve 11 that slides thereover to cover and 10 uncover the port 12 in the intermediate wall portion 6. The intermediate portion of rod 5 has an integral flange or collar 13, and the outer ends of the rod are screw threaded to receive nuts 14, which are drawn tightly 15 against their respective adjacent pistons 2 and 4, piston 2 being clamped against a sleeve 15 on the rod 5, which in turn forces a piston 16 against the rod flange 13. The pistons 2, 4, and 16 may be provided with suitable 20 packing or piston rings 17. Slide valve 11 is recessed at 18 to receive the adjacent tongue 19 presented by the sleeve 15. Both tongue 19 and recess 18 are recessed at 20 to receive a compressed helical spring 21 that maintains 25 slide valve 11 against its seat 10. Cylinders 1 and 3 may be provided with suitable feet or lugs 22, that are apertured to receive bolts 23, that secure them to a suitable support 24 in suitable space relation to one another. 30 Chamber 25, between pistons 2 and 16, communicates with the auxiliary reservoir 26 of the brake system of the car by means of a conduit 27. Chamber 28, to the left of piston 2 in the left end of cylinder 1, communicates 35 with the car branch 29 of the brake-pipe or train line 30 through a conduit 31.

The means for entrapping and storing air from the brake-pipe when the pressure therein exceeds the normal service pressure comprises 40 a volume reservoir 32, that is fed with air from the brake-pipe through conduits 31, 33, 34, check valve 35, and conduit 36. Check valve 35 is maintained against its seat by a compressed helical spring 37, surrounding 45 valve stem 38, and the pressure of the spring 37 may be adjusted by raising or lowering the sleeve 39, externally screw threaded to fit the tapped hole in the upper wall 40 of the valve housing 41. A conduit 42 leads air 50 from the volume reservoir 32 to the chamber 43 to the right of the piston 4 in the cylinder 3, and a needle valve 44 controls the flow of air through the conduit 42. The lower extremity 45 of valve 44 is of piston formation, 55 and operates in a cylinder chamber 46, having its lower end closed by a screw-threaded plug or head 47. The chamber 46 communicates with brake-pipe 30 through car branch pipe 29, conduit 31 and conduit 33. The volume 60 of reservoir 32 is preferably twice the maximum volume of expansible chamber 43. Chamber 43 communicates with the atmosphere through port 48 in the annular wall of cylinder 3 when the piston 4 has reached its 65 extreme left position as indicated in broken

lines in Figure 1. Chamber 49 to the right of piston 16 in cylinder 1 substantially confines the air therein so that it is compressed or rarified according to the direction in which the piston 16 is moving and thereby cushions 70 the moving parts against shock. A pin hole 50 may be provided in the head 51 that closes the end 8 of cylinder 1, the size of the hole being such that the air escapes from the chamber 49 slowly enough to cushion the 75 motor against undue shock, yet rapidly enough to minimize the elasticity of the air cushion sufficiently to prevent a recoil of the pistons. A pin hole 52 is preferably also provided in the head 53 at the right of piston 4 in cylinder 3 to prevent recoil by the formation of an air cushion in chamber 43. 80

Piston rod 5 may be operated manually by a lever 54, pivoted at 55 to any suitable support, such as a lug 56 on the head 57 of cylinder 3, and pivotally connected to rod 5 by a pin 58 borne by said rod and operable in a slot 59 in the lever 54. The lower extremity of lever 54 may be pivoted at 60 to any suitable operating member 61 that extends to a convenient point within reach of the brakeman or switchman. 90

The brake-pipe 30, the angle cocks 62, the hose 63 and associated parts, the air strainer 64, the car branch pipe 29, the cut-out cock 65, the triple valve 66, the pressure retaining valve 67, the auxiliary reservoir 26, and the car brake cylinder 68 are standard and well known parts of an automatic air brake system. It will, therefore, be unnecessary to 100 describe these parts or the manner in which they operate and co-operate. It will be understood, also, that, in the diagram, the dimensions of these parts are out of true proportion to the dimensions of the new parts 105 of the present invention, the former being drawn to a much smaller scale than the latter because their construction is well known and need not be shown in detail. 110

The construction of the novel parts of the apparatus, the manner of assembling them, and the location of their points of connection to an automatic air brake system having been fully described, the mode of operation will be readily understood. When a train has been 115 assembled and is in service, the brake pipe is normally charged with air under a pressure of seventy pounds per square inch, and the movable parts of the apparatus occupy the positions shown in full lines in Figure 1, all 120 the angle cocks 62 and the cut-off cocks 65 being open. If now, a car be disconnected from a train, the angle cocks 62 of the adjoining cars are closed, the hose couplings are disconnected and the angle cocks 62 of the detached car are left open. The pressure in the car section of the brake-pipe then becomes zero, causing the actuation of the triple valve to admit air from the auxiliary reservoir 26 to the brake cylinder 68 and to apply the 125 130

brakes. If, now, it is desired to permit the car to coast or to be rolled independently of the locomotive, as in switching, the brakes must of course be released. To do this, it is merely necessary to pull rod 61 to the left, thereby shifting rod 5 and valve 11 to the left until port 12 is completely opened to the atmosphere thereby permitting the auxiliary reservoir 26, and the brake cylinder 68 communicating therewith to discharge into the atmosphere through conduit 27 and chamber 25, thereby releasing the brakes of the car. When the car is again attached to the train, and its brake-pipe again becomes a part of the train line charged with air under a pressure of seventy pounds per square inch, the piston 2 is pushed toward its extreme right by the compressed air in chamber 28 transmitted thereto from the brake-pipe through conduit 31, the slide release valve 11 again covers the port 12, and permits auxiliary reservoir 26 to be recharged through the automatically operating triple valve 66. Since the release valve 11 is thus closed automatically, the brakeman need not wait at the release valve two minutes after he has opened it, as has heretofore been necessary, in order to close it. It will be observed that valves 44 and 35 are closed in Figure 1, valve 44 being closed by the air pressure exerted against the bottom of piston 45 in chamber 46, and valve 35 being closed by spring 37, the pressure of which is adjusted by the manipulation of threaded sleeve 39 so that it will oppose the lifting of the valve 35 from its seat as long as the pressure in the brake pipe and in the nipple 34 does not exceed seventy-three pounds per square inch. It will, therefore, be apparent that no air from the brake-pipe can pass through the conduit 42 to the chamber 43 to actuate piston 4 to open release valve 11 until the pressure in the brake-pipe exceeds seventy-three pounds per square inch. The engineer of a freight train is not permitted to raise the brake-pipe pressure to more than seventy pounds per square inch, when the train is in service or on the road. However, just prior to detaching the locomotive with the intention of letting the cars of the train remain standing, he may raise the pressure to ninety pounds per square inch. This is seventeen pounds more than is necessary to counterbalance the pressure of the spring 37 of valve 35, consequently valve 35 will be lifted until chamber 32 has been charged with air under a pressure of seventeen pounds per square inch. Now, when the locomotive is cut off while the angle cocks 62 of the cars remain open, the brake-pipe under the cars is discharged, and the air pressure in chambers 28, 34, and 46 is removed, whereupon piston 45 drops, because of its own weight and also because of the seventeen pounds pressure on the top face of the piston 45, thereby opening valve 44 and permitting the compressed air in reservoir 32 to enter chamber 43 through conduit 42, thereby moving piston 4 to its extreme left position, carrying with it rod 5 and valve 11, and opening port 12, thereby discharging the air in the brake cylinder 68 and the auxiliary reservoir 26 to the atmosphere and releasing the brakes automatically. Manifestly, the time and labor needed heretofore to open the release valves by hand was considerable; and the use of the automatic means of the present invention for opening the release valve of an auxiliary reservoir materially expedites operation. It will be observed that, when the train is running with the brakes in release, the pressure on both sides of the piston 2 is seventy pounds per square inch, while the pressure on the left side only of piston 16 is seventy pounds per square inch. The pressure of the air in chamber 25 on pistons 2 and 16 being equal but opposite, no movement of the piston rod can be effected by the compressed air in chamber 25, the stroke toward the right being effected by the compressed air in chamber 28, while the stroke toward the left is effected by the compressed air in chamber 43. It will be understood and appreciated that, while, in the present practice, the brake-pipe service pressure on freight trains is seventy pounds per square inch, it is higher on passenger equipment, and the present invention is not limited for use on trains having a service pressure of seventy pounds, but is applicable to any suitable service pressure that may be now in use or hereafter established, and that the entrapping and storing of the air in the reservoir 32 may be effected by exceeding such service pressure.

It should, also, be understood that the terms "air brake," "air brake system" and the like, wherever they occur in the description and claims, are intended to be comprehensive and to include within their scope devices that employ fluids or elastic fluids other than air but are equivalent thereto in achieving the purpose thereof.

The release-valve of the present invention, also, possesses inherent advantages that render it capable of use for other purposes and in situations outside of an air brake system. For instance, the throttle-valve of a locomotive has a tendency to "stick" and the release-valve of this invention is characterized by the absence of such a tendency, and is therefore a useful substitute therefor. It may, also, be used as a drain-valve for an oil tank, or a drain-valve for gas lines wherever there is a drain basin.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. An automatic air brake system including an auxiliary reservoir and a release valve therefor having in combination therewith an air-driven motor for opening said valve, a reservoir for storing the air that opens said valve, a check valve arranged to admit air from the brake-pipe to the said last mentioned reservoir when the pressure in the brake-pipe rises above its normal service pressure, a valve controlling the flow of air from the last mentioned reservoir to the motor, and means operated by the pressure in the brake-pipe for closing said last mentioned valve.

2. An automatic air brake system including an auxiliary reservoir and a release valve therefor having in combination therewith an air-driven motor for opening said valve, a reservoir for storing the air that opens said valve, a check valve arranged to admit air from the brake-pipe to the said last mentioned reservoir when the pressure in the brake-pipe rises above its normal service pressure, a valve controlling the flow of air from the last mentioned reservoir to the motor, and means operated by the pressure in the brake-pipe for closing said last mentioned valve and by the pressure in the last mentioned reservoir for opening it.

3. An automatic air brake system including an auxiliary reservoir and a release valve therefor having in combination therewith an air-driven motor for operating said valve, an air connection from the brake-pipe to the motor for operating the motor to close the valve, a reservoir for storing the air that opens said valve, a check valve arranged to admit air from the brake-pipe to the said last mentioned reservoir when the pressure in the brake-pipe exceeds the normal service pressure therein, and a valve controlling the admittance of air from the said last mentioned reservoir to the motor for operating the latter to open the release valve, the said last mentioned motor valve having provisions whereby it is maintained closed by the pressure of the air in the brake-pipe.

4. An automatic air brake system including an auxiliary reservoir having in combination therewith a cylinder, a pair of pistons therein rigidly connected to move together and spaced to provide a movable chamber therebetween, an air conduit from the auxiliary reservoir to the said chamber, a port leading from the said chamber to the atmosphere, a valve in the chamber slidably over the port to open and close the same and operated by said pistons, and an air conduit leading into the cylinder space between a cylinder head and an adjacent piston for operating the latter.

5. An automatic air brake system including an auxiliary reservoir having in combination therewith a cylinder, a pair of pis-

tons therein rigidly connected to move together and spaced to provide a movable chamber therebetween, an air conduit from the auxiliary reservoir to the said chamber, a port leading from the said chamber to the atmosphere, a valve in the chamber slidably over the port to open and close the same and operated by said pistons, and a conduit leading from the brake-pipe into the cylinder space between a cylinder head and an adjacent piston for operating the latter.

6. An automatic air brake system including an auxiliary reservoir and a release valve therefor having in combination therewith a cylinder, a piston therein connected to said valve to close it when moving in one direction and to open it when moving in the opposite direction, means for collecting and storing air from the brake-pipe when the pressure therein exceeds the normal service pressure, and a valve operated by the discharge of the brake-pipe for admitting air from said air storing means to the said cylinder for operating said piston to open the valve.

7. An automatic air brake system including an auxiliary reservoir and a release valve therefor having in combination therewith a cylinder, a piston therein connected to said valve to close it when moving in one direction and to open it when moving in the opposite direction, means for collecting and storing air from the brake pipe when the pressure therein exceeds the normal service pressure, and a valve operated by the discharge of the brake pipe for admitting air from said air storing means to the said cylinder for operating said piston to open the valve, said cylinder having an opening to the atmosphere that communicates with the space between the piston and the cylinder head when the piston has reached the end of its opening stroke, thereby to exhaust the air that drove the piston.

8. An automatic air brake system including an auxiliary reservoir and a release valve therefor operable in opposite directions for opening and closing the valve, respectively, a piston for closing the valve, a piston for opening the valve, cylinder means in which said pistons operate, a conduit leading from the brake-pipe to the space between the first piston and its adjacent cylinder head for closing the valve, means for entrapping and storing air from the brake-pipe when the pressure therein exceeds the normal service pressure, a conduit leading from said storing means to the space between the second piston and its adjacent cylinder head for opening the valve, and a valve controlling the said last mentioned conduit and maintained in closed position by the pressure of the air in the brake-pipe.

9. An automatic air brake system including an auxiliary reservoir and a release valve

therefor having in combination therewith an air-driven motor for opening said valve, means for entrapping air when the pressure in the brake pipe is charged above its normal service pressure and means for discharging said entrapped air to operate said motor, said means being controlled by the discharge of the brake pipe.

10 10. An automatic air brake system including an auxiliary reservoir and a release valve therefor having in combination therewith an air-driven motor for opening said valve, a reservoir for storing excess pressure of air from the brake pipe and means controlled by the pressure in the brake pipe for discharging air into said motor.

11 11. An automatic air brake system including an auxiliary reservoir and a release valve therefor having in combination therewith an air-driven motor for opening said valve, a reservoir for storing the air that opens said valve, a check valve arranged to admit air from the brake pipe to the said last mentioned reservoir when the pressure in the brake pipe rises above its normal service pressure and a valve controlling the flow of air from the last mentioned reservoir to the motor.

12 12. An automatic air brake system including an auxiliary reservoir and a release valve therefor having in combination therewith automatic mechanism for opening the valve, said mechanism having means to place said mechanism in a condition to be operated when the brake-pipe is charged above its normal service pressure and means for discharging air to operate said mechanism, said means being controlled by the discharge of the brake-pipe.

13 13. An automatic air brake system including an auxiliary reservoir, a release valve for the reservoir, and a pneumatically operated mechanism for actuating said valve, said mechanism having means to place it in condition to be operated when the brake pipe is charged above its normal service pressure, and means for operating said mechanism to actuate said release valve, said means being controlled by the discharge of air from the brake pipe.

14 14. An automatic air brake system including an auxiliary reservoir, a release valve for the reservoir, and a pressure operated mechanism for actuating said valve, said mechanism having means to place it in condition to be operated when the brake pipe is charged above its normal service pressure, and means for operating said mechanism to actuate said release valve, said means being controlled by the discharge of air from the brake pipe.

15 15. An automatic air brake system including an auxiliary reservoir, a release valve for the reservoir, and a pressure operated mechanism for actuating said valve, said mechanism having means to place it in condition to be operated by the storage of pressure

therein when the brake pipe is charged above its normal service pressure, and means for releasing the pressure in said mechanism to actuate said release valve, said means being controlled by the discharge of air from the 70 brake-pipe.

In testimony whereof I hereunto affix my signature.

JESSE N. WOOD.
